UNITED STATES PATENT OFFICE.

HARRY BARTH, OF SAN FRANCISCO, CALIFORNIA.

TOY.

1,329,575.

Specification of Letters Patent.

Patented Feb. 3, 1920.

Application filed October 7, 1919. Serial No. 329,109.

To all whom it may concern:

Be it known that I, HARRY BARTH, a citizen of the United States, residing at San Francisco, in the county of San Francisco 5 and State of California, have invented certain new and useful Improvements in Toys, of which the following is a specification.

This invention relates to improvements in toys, and more particularly to toys of the 10 doll type.

One of the objects of the present invention is to provide a toy of the above general character which may be inexpensively manufactured and sold and of such shape and 15 general appearance as to portray certain human characteristics in one manner or another. A further object is to provide a doll toy adapted to illustrate or portray a peculiar characteristic or hobby of the person 20 to whom the doll might be presented. Other objects will be in part obvious and in part hereinafter pointed out.

The accompanying drawing illustrates several of the various possible embodiments 25 of the invention, and in such drawing corresponding reference characters denote similar parts.

Figure 1 is a front elevational view of a portion of a toy doll illustrating one embodiment of the invention.

Fig. 2 is a sectional view in normal position.

Fig. 3 is a similar view showing a modification, and

Fig. 4 is a fragmentary sectional view showing a still further modification.

The present invention as herein illustrated shows the head 5 of a doll in conventional form. It is to be understood however that 40 this head and the body to which it is attached may be of any desired size, shape and color, and dressed correspondingly to represent an old or young person, male or female, white or colored, as desired.

The principal feature of the invention resides more particularly in the countersunk recess or opening 6 appearing preferably 45 on the front of the doll across the forehead. It may also occur on the back as in Fig. 2 as indicated at 7. This may be an actual opening through to the interior or a countersunk part adapted to be closed by a movable or hinged door 8 or bodily removable portion 9, as shown in Fig. 4. The door may 50 be opened in any desired way as by knob 55 10. Back of this door or closure is a view

11 marked to imitate or illustrate a portion of the human brain in the central part of which is depicted some article or thing adapted to indicate the peculiar hobby of 60 that person or the subject in which the person is most particularly interested. This idea is based on the assumption that almost every individual has such a hobby and for example one who devotes a large part of 65 his spare time to golf will appreciate the illustration shown in Fig. 1, while another being more interested in baseball; horse racing, art, music or the like would have such hobby illustrated in a somewhat similar 70 and suitable manner. The views may be in the form of cards 12 of celluloid or other flexible material, and of relatively large assortment, whereby they could be easily inserted in the countersunk portion and se- 75 cured therein in any desired manner according to fancy.

It is believed that the construction and objects sought to be accomplished will be clear from the above description, and a further statement thereof is doubtless unnecessary.

I realize that considerable variation is possible in the details of the construction herein shown, and I do not intend to limit 85 myself thereto, except as pointed out in the following claims, in which it is my intention to claim all the novelty inherent in the device as broadly as is permitted by the state of the art.

Having thus described my invention what I claim as new and desire to secure by Letters Patent is:

1. An article of the character described comprising a doll's head having a countersunk recess, a removable picture adapted to be placed therein, and a cover for said recess fitting in said countersunk portion.

2. An article of the character described comprising a doll's head having recesses on 100 the front and rear sides thereof, pictures adapted to be inserted in said recesses, and removable closures adapted to cover said picture and lie flush with the surface of the head.

In testimony whereof I affix my signature in presence of two witnesses.

HARRY BARTH.

Witnesses:

E. L. CHLOUSE,
L. L. JAMES, Jr.
